UNITED STATES PATENT OFFICE.

ADOLPH SCHNEIDER, OF TRINIDAD, COLORADO.

BOTTLING-MACHINE.

SPECIFICATION forming part of Letters Patent No. 651,274, dated June 5, 1900.

Application filed March 15, 1900. Serial No. 8,827. (No model.)

To all whom it may concern:

Be it known that I, ADOLPH SCHNEIDER, a citizen of the United States, residing at Trinidad, in the county of Las Animas, in the State of Colorado, have invented new and useful Improvements in Bottling-Machines, of which the following is a specification.

My invention relates to machines for bottling malt liquors; and the object thereof is to provide a machine that will fill such liquor into bottles automatically without producing foam. I accomplish these objects by the mechanism described herein and illustrated in the accompanying drawings, forming a part hereof, in which—

Figure 1 is a perspective view of my machine, showing it applied to two barrels of malt liquor. Fig. 2 is a side view of the liquor-distributing tank. Fig. 3 is an end view of the same. Fig. 4 is a longitudinal vertical section of the liquor-distributing tank. Fig. 5 is a cross-section on line 5 5 of Fig. 4. Fig. 6 is a sectional view of my bottle-filling tube and connecting mechanism. Fig. 7 is a front view of the mechanism shown in Fig. 6, partly cut away. Fig. 8 is a side view of my bottle-holding bar. Fig. 9 is a cross-section on line 9 9 of Fig. 3.

In the drawings, A represents a drum charged with compressed air or other expandable gas, having a cock A' to control the flow of air therefrom, and is connected by pipe B, preferably a flexible piece of hose, with tapping-bung C, driven into barrel D, filled with malt liquor, which permits the air to be discharged upon the top of the liquor. An air-compressor or any other suitable mechanism to supply air or gas under pressure may be substituted for drum A, and for barrel D any other suitable receptacle may be used. On pipe B is vacuum-valve E, which regulates the air-pressure through pipe B.

F is a pressure-gage to indicate the pressure in pipe B.

G is a pipe which extends through bung C to the bottom of barrel D.

H is a cock attached at one of its ports to pipe G for closing the connection between the barrel and the distributing-tank when it is necessary to connect a fresh barrel of liquor with the machine. To the other port of cock H is attached a pipe I, preferably a flexi-

ble pipe, which is connected at the other end to distributing-tank J, through which cock H and pipe G liquor passes from barrel D into 55 distributing-tank J. Tank J is mounted in frame K and is adjustable therein as to height by set-screws L, which screw into guide-flanges M, affixed to the ends of tank J, and pass through slots K' in the frame and clamp 60 said flanges against frame K. Tank J is preferably constructed in two parts, so that the interior can be easily cleaned. The upper portion or cover J' is hinged to the lower body portion J'' by hinge N, and between the 65 cover and body is a rubber gasket O to make an air-tight joint when the cover is fastened upon the body, which is done by turning the cover to its proper position on the body, then turning bolts P, pivoted to the body, so that 70 they pass through lugs J'', affixed to the cover, and the nuts P' are screwed down, so as to draw the cover down tightly on the gasket. At the top of tank J is a pressure-regulating valve R, to regulate the air or gas pressure 75 in tank J. To the top of tank J, preferably at or near valve R, is connected pipe S, having stop-cock T. Pipe S is provided with a pressure-gage U to indicate the pressure in tank J, and is connected with pipe B by pipe 80 V, preferably flexible hose. In the bottom of tank J is ball-cock W, which controls the admission of liquor into tank J through pipe I and is adapted to prevent the liquor in the tank from rising above a predetermined 85 height. In the bottom of tank J is screwed one or more ball-valves X, having casing X', in which are two orifices a and b, which open into tank J, and opposite thereto is a slot e. In orifice b is affixed a small vent-tube c, extending upward into tank J above the highest level of the liquor therein. Passing through and filling the port in valve X is the filling-tube d, which passes through a slot e in casing X' and has a vertical movement therein. Within tube d is partition-wall g, which divides tube d into two independent channels h and i for a portion of its length, each having an independent mouth. Channel i has its mouth k at such distance from the end of tube 90 d as it is desired to have the liquor rise in the bottle when it is being filled. When a bottle is on tube d in position to be filled, channel h at its inner end registers with ori-

ifice *a* and channel *i* registers with orifice *b*, and when the bottle is removed valve *X* is turned to cut off the registration of the channels with orifices *a* and *b*. Surrounding tube *d* in close proximity to valve *X* is a chamber *m*, preferably circular, in which is a rubber gasket *n*, of rubber or other yielding material, having a cylindrical opening therein adapted to fit over the mouth of the bottle, which opening terminates in an annular wedge-shaped groove, the inner part of the gasket, which forms the groove, being adapted to be wedged between the inner side of the mouth of the bottle *p* and tube *d* and make an air-tight joint between them. Any other form of gasket which will make an air-tight joint between the bottle and the tube may be used instead of the one shown. Chamber *m* is attached to valve *X* by a short nipple *r*, which screws into each. Affixed to valve-casing *X'*, or, if preferred, to tank *J*, is resilient bar *s*, to the outer end of which is affixed a yoke *t*, preferably resilient, to grasp and hold the neck of a bottle when placed on tube *d* in position for filling, and make the joint between the bottle and tube air-tight.

My machine is operated as follows: Tubes *d* are turned to the position shown by the dotted lines in Figs. 3 and 6. One or two barrels of malt liquor are connected to the bottling-machine, as shown in Fig. 1. The air or gas pressure is then regulated to, say, five pounds, as indicated by gages *F* and *U*. Cock *T* is then closed and valve *R* is set at a pressure (say of four and one-half pounds) that will permit the five pounds pressure on the top of the liquor in the barrel to force the same into tank *J* until the flow is automatically cut off by ball-cock *W*, when the machine is ready for filling bottles. Bottles *p* are then placed on the tubes *d*, which are then turned so as to force the neck of the bottle into yoke *t* and the head of the neck of the bottle into gasket *n*, where it is held by the resiliency of bar *s* and yoke *t*, and the gasket makes an air-tight joint between the bottle *p* and tube *d*. This movement of tube *d* brings channel *h* in register with orifice *a* and channel *i* in register with orifice *b*, and the liquor from the tank flows into the bottle and the air in the bottle passes into the tank through tube *c*. As soon as the liquor rises and covers orifice *k* the flow of liquor into bottle *p* ceases and they are ready to be removed. Pipe *d* is returned to the position shown by the dotted lines in Figs. 3 and 6, when the bottle is taken off the tube and the flow of liquor therethrough is cut off.

My machine can be constructed with a capacity to hold as many bottles and barrels as desired.

Having described my invention, what I claim is—

1. A machine for bottling malt liquors, comprising suitable means to supply air under pressure, a pipe connecting such air-supply with a tapping-bung; a tapping-bung adapted

to be driven into a receptacle for holding malt liquor, and to permit air to be discharged upon the top of the liquor; a pipe extending through said tapping-bung to the bottom of the receptacle holding the liquor; a cock on the upper end of the pipe, extending through said bung, adapted to shut off the flow of liquor therethrough when desired; a pipe connecting said cock with a liquor-distributing tank; a liquor-distributing tank; ball-valves screwed into the bottom of said tank, and having a casing provided with two orifices opening into said tank, and a slot opposite thereto; an air-vent tube in one of said orifices, adapted to extend upward above the liquor in said tank; a filling-tube, divided into two channels for a portion of its length, each channel having an independent mouth exterior the valve, the inner end of which is adapted to fill the port in said valve, and on a certain movement of the valve to cause the channels therein to register with the orifices in the casing opening into the tank, and at other times to shut off said channels from said orifices; a gasket on said tube, exterior said valve, adapted to make an air-tight contact between the bottle and said tube, when a bottle is in place to be filled; a resilient bar affixed to the casing of said valve; a yoke affixed to the end of said bar; said bar and yoke adapted to hold the bottle in contact with the gasket and make an air-tight connection between the bottle and tube.

2. In a machine for bottling malt liquors, the combination of suitable means to supply air under pressure, a pipe connecting such air-supply with a tapping-bung; a tapping-bung adapted to be driven into a receptacle for holding malt liquor, and to permit air to be discharged upon the top of the liquor; a pipe extending through said tapping-bung to the bottom of the receptacle holding liquor; a cock on the upper end of the pipe, extending through said bung, adapted to shut off the flow of the liquor therethrough when desired; a pipe connecting said cock with a liquor-distributing tank; a liquor-distributing tank; ball-valves screwed into the bottom of said tank, and having a casing provided with two orifices opening into said tank, and a slot opposite thereto; an air-vent tube in one of said orifices, adapted to extend upward above the liquor in said tank; a filling-tube divided into two channels for a portion of its length, each channel having an independent mouth exterior the valve, the inner end of which is adapted to fill the port in said valve, and on a certain movement of the valve to cause the channels therein to register with the orifices in the casing opening into the tank, and at other times to shut off said channels from said orifices; a gasket on said tube, exterior said valve, adapted to make an air-tight contact between the bottle and said tube when a bottle is in place to be filled; a resilient bar affixed to the casing of said valve; a yoke affixed to the end of said bar;

said bar and yoke adapted to hold the bottle in contact with the gasket and make air-tight connection between the bottle and tube, with bottles and malt liquor in a receptacle, substantially as described herein.

3. A machine for bottling malt liquors, comprising drum A; pipe B connecting said drum with bung C; bung C, adapted to be driven into barrel D, and to permit the air to be discharged therethrough on the top of the liquor in said barrel; barrel D; pipe G, adapted to pass through bung C and into barrel D to the bottom thereof; cock H attached to pipes G and I; pipe I attached to cock H and to distributing-tank J; distributing-tank J; ball-valves X in casing X'; casing X' affixed to tank J; orifices a and b in said casing, opening into tank J, and slot e opposite said orifices; vent-tube c in orifice b; filling-tube d, filling the port in valve X and passing through slot e and divided into channels h and i; gasket n on said filling-tube; resilient bar s affixed to valve-casing X'; yoke t affixed to said bar; said bar and yoke being adapted to hold a bottle on the filling-tube in air-tight contact with gasket n.

4. In a machine for bottling malt liquors, the combination of a distributing-tank; a ball-cock in said tank to govern the height

of the liquor therein; a ball-valve connected thereto by the casing thereof; orifices in said casing opening into said tank; a slot in said casing opposite the orifices; a vent-tube in one of the orifices opening into the tank; adapted to extend above the liquor therein; a filling-tube divided for a portion of its length into two independent channels having separate mouths extending through the slot in the casing; the inner end of which filling-tube fills the port in said valve; a gasket on said tube, adapted to enter the mouth of the bottle to be filled; a resilient bar affixed to the casing of the valve; a yoke affixed to the end of said bar; said bar and yoke adapted to hold the bottle in contact with the gasket and produce an air-tight joint between the bottle and tube, with a bottle and a suitable liquor-supply, and means to apply pressure thereto to force the liquor into the bottle.

In witness that I claim the foregoing I have hereunto subscribed my name, this 9th day of March, 1900, at Los Angeles, California.

ADOLPH SCHNEIDER.
